Attorney

UNITED STATES PATENT OFFICE

JACOB E. NEAHR, OF SCARSDALE, NEW YORK

SMOKER'S UTENSIL

Application filed June 25, 1929. Serial No. 373,645.

This invention relates to smokers' utensils, and particularly to provision for pinching cigars or cigarettes, and disposing of ashes and débris.

5 One feature of the invention is the provision of a simple article of desk or table ornament, which may be readily saleable at a substantial price, but which can be manufactured at very low cost, and which will 10 have efficient provision therein for pinching cigars and possess other advantages desirable in smokers' sets.

In the preferred form of the invention, an ash-receiver may be fabricated in the form 15 of a simple bowl of ornate appearance, from the floor of which rises a hollow stem or trunk, which, in some cases, may be integral with the bowl. The top of the hollow trunk is broadened, and is surmounted by a cap, 20 which not only serves as a top for the trunk, but also as a finger-piece, whereby the top may be lifted, thus making an opening into which the burned end of a cigar or cigarette 25 may be thrust. Then the finger-piece may be pressed down to pinch the cigar between the same and a pinching table, which is arranged within the upper portion of the hollow trunk, the latter flaring at its top to afford room for the pinching table. Said lift-

30 able top has a guiding shank or stem which extends down within the trunk, and which serves as a stop against which the burned end of the cigar or cigarette is thrust, thus positioning the same at the proper point for 35 pinching. The pinching table has numerous perforations, through which the pinched-off ashes may drop into the interior of the hollow trunk, which, although slender, may have sufficient capacity to accommodate a 40 great amount of ashes.

Upon removing the pinched cigar or cigarette, the top may be rotated, so as to scrape the ashes through the perforations in the pinching table, so that they will drop into 45 the interior of the trunk.

It is also an aim of the invention to eliminate the great loss which occurs from burning cigars or cigarettes being laid carelessly upon a rest, so that they fall off therefrom 50 and drop unnoticed upon an expensive table-

cloth or table-top, burning the same and thereby ruining it.

The top of the trunk is made of spheroidal form and provided with cigar-rests formed therein, preferably one crosswise of the other, thereby gaining the advantage that if the cigarette should fall off from the rest, it will fall into the bowl and not outside thereof. 55

The pinching table is of substantially less diameter than the flaring top of the main trunk, so as to leave an annular opening around the pinching table, out of which the accumulated ashes may be shaken when the bowl is tipped over.

The movable top may have a shallow brim, 60 which, for neatness, may enclose the flaring top edge of the main trunk, thus giving the article a simple and neat appearance.

In one form of the invention, the main trunk may be made of metal, and have a post 70 or bolt passing down through the bowl where it may be secured by a nut. In other forms of the invention, the trunk may be made integral with the bowl.

Other features and advantages will here- 75 inafter appear.

In the accompanying drawings,

Figure 1 is a perspective view, partly in section, of the present invention in one form.

Figure 2 is a vertical section through the 80 hollow central column or trunk.

Figure 3 is a vertical section through the novel device, illustrating the pinching of a cigarette.

Figure 4 is a perspective view of a per- 85 forated cigarette-pinching table or plate and the internal post upon which it is mounted.

Figure 5 is a perspective view showing the emptying of ashes from the interior of 90 the hollow trunk.

Figure 6 is a view showing the hollow trunk or column and the main bowl all made in one piece of glass or other molded ware.

Within a bowl 10 of glass, ceramic wear, or the like, is erected a hollow central column 95 or trunk 11, whose base 12 is preferably bolted to the bottom 20 of the bowl by means of an internal post 13, having an annular seat-flange 14, said post standing within the hollow 15 of the trunk or column, and said 100

flange 14 fitting in said hollow and being drawn down upon the bottom of the hollow post at 16 by means of a nut 17, which is secured upon the threaded projecting lower end 18 of the post. The post extends down through a hole 19 in the floor 20 of the bowl, and preferably is threaded into said opening 19. In this manner, the trunk 11 is rigidly supported within the bowl, which 10 serves as a receiver for burned cigars and other débris.

The ornamental quality of the novel device is enhanced by means of a cap 21 15 surmounting the trunk. This may be in the form of a circular disk having a spheroidal top surface and made of burnished brass or other attractive metal, and the top of said cap may be given a star-like ornamentation by means of shallow cross-grooves 22 formed 20 therein. These cross-grooves may be used as cigar or cigarette rests, as at Figure 1. The cap 21 is sufficiently small in diameter as to leave an abundance of space between its edge and the surrounding brim of the 25 bowl, so that if a cigar should be accidentally knocked off from the rest, it would fall within the bowl and not upon the table upon which the bowl rests, thus avoiding liability of burning or damage to an expensive table 30 top or rug.

The trunk 11 may be made of a suitable height, preferably sufficient to bring the ornamental cap 21 a little above the surrounding edge of the bowl, as shown in Figure 35 6.

The principal use of this ornamental cap 21 is to serve as a cigar or cigarette extinguisher. For this purpose the cap serves as 40 the upper jaw of the extinguisher, and preferably is movable. It may be lifted from its normal position, and cigar may be inserted under the same, that is, between said cap and the upper edge 23 of a hollow trunk. For guiding the cap 21, it is fixed upon the 45 top of a central stem 24, which slides up and down in a central perforation 25 formed in the internal post 13, said stem rising above said post and being riveted at 26 to the center of the extinguisher table or plate, and being 50 threaded at its lower end and provided with a flange in the form of a nut 27 threaded thereon. By grasping the cap 21 it may be lifted, until a rubber washer 28, resting upon the nut 27, comes into contact with the top 55 29 of the hollow 30 provided in the bottom portion of the post 13.

When the cap is so drawn up, the burned end of a cigarette or cigar may be thrust under the cap until it comes to rest with its 60 end against the central rod 24, which serves as a gage, and upon pressing down the cap 21 the cigarette or cigar is extinguished. The cigar by this means is pressed down upon a plate or table 31, which occupies a position 65 within the top of the trunk 23, and is nor-

mally concealed, this plate 31 being foraminous or provided with numerous perforations 32, to permit the ashes to drop down within the hollow trunk 11, as at 33. Said pinching table 31 is riveted to the top of the fixed post 13, as at 34.

The cap 21 is of greater diameter than the brim 23 of the hollow trunk, so as to conceal the edge 23, and said cap may be provided in its bottom with an undercut circular 75 groove 35, within which is received the top edge 23, so that the cap sets down over the edge of the brim 23. Said groove may be made wide, to give clearance for the pinched cigarette or cigar, and avoid cutting off the 80 unburned end of the same.

At Figure 6, the trunk 36 is made in one piece with the bowl of molded wear, but in other respects may be the same as at Figure 3, in which the trunk 11 is formed of bronze 85 or other ornamental metal.

Variations may be resorted to within the scope of the invention, and portions of the improvements may be used without others.

Having thus described my invention, I 90 claim:

1. A smoker's utensil including a bowl forming a main receptacle and having a floor, a hollow trunk rising from the floor of the bowl and open at its top, a cigar-pinching 95 plate at the top of said trunk, and a cap mounted upon said trunk and movable to co-operate with said plate in pinching a cigar, said plate being foraminous to permit the pinched-off ashes to fall within the trunk. 100

2. A smoker's utensil including a bowl forming a main receptacle and having a floor, a hollow trunk rising from the floor of the bowl and open at its top, a cigar-pinching plate at the top of said trunk, and a cap 105 mounted upon said trunk and movable to co-operate with said plate in pinching a cigar, said plate being foraminous to permit the pinched-off ashes to fall, and said cap being revoluble to scrape the ashes from the 110 plate into the perforations through which they may drop into the trunk.

3. A smoker's utensil including a bowl forming a main receptacle and having a floor, a hollow trunk rising from the floor of the 115 bowl and open at its top, a cigar-pinching plate at the top of said trunk, and a cap mounted upon said trunk and movable to co-operate with said plate in pinching a cigar, said plate being foraminous to permit the 120 pinched-off ashes to fall within the trunk, said plate being of smaller diameter than said trunk, so as to leave an annular surrounding space through which the accumulation of ashes may be emptied from the trunk. 125

4. A smoker's utensil including a bowl forming a main receptacle and having a floor, a hollow trunk rising from the floor of the bowl and open at its top, a cigar-pinching plate at the top of said trunk, and a cap 130

mounted upon said trunk and movable to co-operate with said plate in pinching a cigar, said plate being foraminous to permit the pinched-off ashes to fall within the trunk, 5 said plate being of smaller diameter than said trunk, so as to leave an annular surrounding space through which the accumulation of ashes may be emptied from the trunk, the top of the trunk being broadened to accommodate said plate, and said top having a cigar-rest provided directly thereon so that the cigar in falling off from the rest will fall within the bowl.

5. A smoker's utensil including a bowl 15 forming a main receptacle and having a floor, a hollow trunk rising from the floor of the bowl and open at its top, a cigar-pinching plate at the top of said trunk, a cap mounted upon said trunk and movable to co-operate with said plate in pinching a cigar, 20 said cap having a guiding stem extending downwardly within the trunk, and means being provided to guide said stem; said stem serving as a stop against which the burned 25 end of a cigar is thrust preparatory to pinching.

6. A smoker's utensil including a bowl 30 forming a main receptacle and having a floor, a hollow trunk rising from the floor of the bowl and open at its top, a cigar-pinching plate at the top of said trunk, a cap mounted upon said trunk and movable to co-operate with said plate in pinching a cigar, 35 said cap having a guiding stem extending downwardly within the trunk, means being provided to guide said stem; said stem serving as a stop against which the burned end of a cigar is thrust preparatory to pinching, said bowl being made separately from 40 said trunk, a post passing down through the trunk and through the bottom of the bowl, and means co-operative with said post to fasten said trunk to the bottom of the bowl.

7. A smoker's utensil including a main 45 bowl and a hollow trunk standing therein, means for bolting said trunk to the bottom of the bowl, including a post having an annular seat-flange fitting in the hollow of the trunk, said post having a projection extending down through the bottom of the bowl, 50 and a fastening nut threaded upon said projection.

8. A smoker's utensil including a bowl 55 forming a main receptacle and having a floor, a hollow trunk rising from the floor of the bowl and open at its top, a cigar-pinching plate at the top of said trunk, a cap mounted upon said trunk and movable to co-operate with said plate in pinching a cigar, 60 and cross-grooves formed in the top of said cap to serve as cigar-rests, said cap being of substantially small diameter compared with the breadth of the bowl, so that the cigar falling off from the cigar-rest will fall within 65 the bowl.

9. A smoker's utensil including a bowl forming a main receptacle and having a floor, 70 a hollow trunk rising from the floor of the bowl and open at its top, a cap for said trunk serving as the upper jaw of a cigar-extinguisher, and a co-operating cigar-rest or plate, said cap and plate being relatively movable, and provision being made for pinched-off ashes to drop within the hollow trunk.

10. A smoker's utensil including a bowl forming a main receptacle and having a floor, 75 a hollow trunk rising from the floor of the bowl and open at its top, a cap for said trunk serving as the upper jaw of a cigar-extinguisher, and a co-operating cigar-rest or plate, said cap and plate being relatively movable, 80 and provision being made for pinched-off ashes to drop within the hollow trunk, said plate being formed with ash-discharging perforations, and space being left between said plate and the brim of the trunk through which the accumulation of ashes may be emptied.

11. A smoker's utensil including a bowl forming a main receptacle and having a floor, 85 a hollow trunk rising from the floor of the bowl and open at its top, a cap for said trunk serving as the upper jaw of a cigar-extinguisher, a co-operating cigar-rest or plate, 90 said cap and plate being relatively movable, said cap and plate being relatively movable, 95 and provision being made for pinched-off ashes to drop within the hollow trunk, said plate being formed with ash-discharging perforations, and space being left between said plate and the brim of the trunk through 100 which the accumulation of ashes may be emptied, said cap being fixed upon the top of a central stem, and a post mounted within said trunk and having a central perforation in which said stem slides up and down.

12. A smoker's utensil including a bowl forming a main receptacle and having a floor, 105 a hollow trunk rising from the floor of the bowl and open at its top, a cap for said trunk serving as the upper jaw of a cigar-extinguisher, a co-operating cigar-rest or plate, 110 said cap and plate being relatively movable, and provision being made for pinched-off ashes to drop within the hollow trunk, said plate being formed with ash-discharging perforations, and space being left between said plate and the brim of the trunk through 115 which the accumulation of ashes may be emptied, said cap being fixed upon the top of a central stem, and a post mounted within said trunk and having a central perforation in which said stem slides up and down, a nut being threaded upon said stem to serve as a guide-flange and stop.

13. A smoker's utensil including a bowl 125 forming a main receptacle and having a floor, a hollow trunk rising from the floor of the bowl and open at its top, a cigar-pinching plate at the top of said trunk, and a cap mounted upon said trunk and movable to 130

co-operate with said plate in pinching a cigar, said plate being foraminous to permit the pinched-off ashes to fall, and said cap being revoluble to scrape the ashes from the plate into the perforations through which they may drop into the trunk, said cap being of greater diameter than the brim of the hollow trunk and concealing the edge of said brim.

14. A smoker's utensil including a bowl
10 forming a main receptacle and having a floor, a hollow trunk rising from the floor of the bowl and open at its top, a cigar-pinching plate at the top of said trunk, and a cap mounted upon said trunk and movable to co-
15 operate with said plate in pinching a cigar, said plate being foraminous to permit the pinched-off ashes to fall, and said cap being revoluble to scrape the ashes from the plate into the perforations through which they may drop into the trunk, said cap being of greater diameter than the brim of the hollow trunk and concealing the edge of said brim, and the cap having at its bottom an undercut circular groove within which is
20 received the top edge of the trunk.
